UNITED STATES PATENT OFFICE

98,802

DESIGN FOR A TEXTILE FABRIC

Curt Erwin Forstmann, Montclair, N. J.

Application May 18, 1935, Serial No. 56,907

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design pattern is a series of inclined stripes, each stripe consisting of a series of figures spaced apart, each figure comprising three long dashes parallel to each other and to the weft direction of the fabric, the dashes being of irregular length and shaggy in character.

I claim:

The ornamental design for a textile fabric as shown and described.

CURT ERWIN FORSTMANN.
